UNITED STATES PATENT OFFICE.

JESSE M. SMITH, OF PITTSBURGH, PENNSYLVANIA.

BLOW-OUT PATCH.

1,269,124.

Specification of Letters Patent. Patented June 11, 1918.

Application filed September 19, 1917. Serial No. 192,083.

To all whom it may concern:

Be it known that I, JESSE M. SMITH, a citizen of the United States, and residing in the city of Pittsburgh, in the county of Allegheny and State of Pennsylvania, have invented or discovered new and useful Improvements in Blow-Out Patches, of which the following is a specification.

My invention comprises a new and improved blow-out patch for pneumatic tires. The object in view is the provision of means whereby the hole or rupture in the shoe of a pneumatic tire may be quickly and readily mended so that the tire may be re-inflated, if necessary, and the travel of the vehicle resumed without stopping to make repairs by the operation of vulcanizing.

My improved patch member consists of a plate of metal, preferably of ductile metal, such as malleable cast metal, aluminum or mild steel, provided on one face with integral attaching or nailing studs which are driven into the material of the shoe, which plate is positioned to cover the rupture or hole in the shoe. The studs preferably, at least in some instances, are long enough to protrude through the shoe and be clenched at the opposite surface of the latter. I prefer to apply my improved patch to the inner surface of the shoe, but, if desired, the patch may be applied to the outer surface of the shoe, or two patches may be used, one on the inner surface and one on the outer surface of the shoe. The plate is preferably curved to fit the surface to which it is to be applied or the ductility of its material may enable it to be bent into the proper curvature while it is being hammered into place.

In the accompanying drawings, Figure 1 is a cross-sectional view of a pneumatic tire, including both the outer shoe and the inner tube, and showing one of my improved patches applied to the inner surface of the shoe with the inner tube bearing against said patch; Fig. 2 is a broken similar view, with the inner tube omitted, showing the patch applied to the exterior surface of the shoe; Fig. 3 is a like view showing two patches in use, one applied to the inner surface and one applied to the outer surface of the shoe, and Fig. 4 is a face view of one of the patches showing the integral studs.

The following is a detailed description of the drawings, reference being first had to Fig. 1 of the drawings.

A represents the tire shoe and B the inner tube. C represents a rupture or hole in the shoe, such as is frequently the result of a blow-out or other causes.

D represents my improved metal blow-out patch which consists of a plate, preferably made of ductile metal, and provided on one face with a plurality of integral studs of nail-like form, which are driven into the material of the shoe around the rupture or hole to secure the plate in position to cover the weakened portion of the shoe. The plate should be of sufficient area to cover enough of the shoe about the rupture or hole to enable the studs to obtain a secure grip on the shoe to prevent accidental loosening of the patch, and the patch is preferably curved to substantially the surface to which it is to be applied. Such fit need only be approximate, as the ductility of the metal results in the plate being bent into a snug fit as its studs are driven into the shoe. The studs may be only of sufficient length to enter into the material of the shoe, or they may be of sufficient length to extend through the shoe and be clenched on the opposite surface of the latter. I have shown my patch provided both with studs which do not and which do extend through the shoe—an arrangement which I consider practical and preferable.

The number of the studs provided may of course be varied, so long as sufficient studs of the proper character to assure a secure attachment of the patch are provided.

The edges of the exposed face of the patch plate are preferably beveled down so as to make a smooth, relatively thin edge merging with the surface of the shoe to prevent tear or pinching of the inner tube when the vehicle is in motion. For the same purpose the corners of the plate are rounded.

When a blow-out occurs, the tire is removed and the portion of the inner tube adjacent to the blow-out pulled out to expose the inner surface of the shoe. The patch is then put into position and hammered into place with its studs driven into or through the material of the shoe, the protruding ends, if any, of the studs being clenched as shown. The hammering of the patch into position may be done by means of a hammer, the head of a wrench or even a stone picked up at the roadside.

The operation of hammering the patch

into place will cause the plate, of ductile metal, to conform snugly with the contour of the surface of the shoe. To facilitate this bending of the plate to proper curvature, I prefer to make the plate itself of relatively thin gage so as to yield with comparative ease to the bending action. In the drawings, for the sake of clearness of illustration, the plate is shown relatively 10 rather thicker than will probably be the case in standardized practice.

When the patch has been thus applied, the inner tube is again replaced and blown up and the tire put back on the wheel, and 15 the vehicle may then resume its trip.

Where the patch is to be applied on the exterior surface of the tire, as in Fig. 2, the patch of course is curved in the opposite direction to that above described, the 20 studs being on the concaved surface, instead of the convex surface.

In such case also, some or all of the 25 studs may be of sufficient length to protrude through the shoe and be clenched against its opposing face, the clenching being sunk into the surface of the shoe to avoid rubbing against the wall of the inner tube. In Fig. 3, I show patches applied to both 30 surfaces of the shoe to cover the blow-out, one of the patches, such as the inner patch being first put in place and its longer studs clenched, and the second patch being then 35 put in place and its longer studs clenched against the first plate.

It is evident that by the use of my 40 improved patch, the tire may be quickly repaired and the travel of the vehicle resumed without resorting to the tedious and expensive operation of vulcanizing the blow-out.

I am aware that attempts have been made 45 to form blow-out patches of flexible or elastic material, such as leather, fabric or rubber, or combinations of such material, with attaching nails having their heads secured to or embedded in the material of the patch, but I understand that such patches have never met with commercial success. One of the inherent faults of such devices is 50 that their flexibility or elasticity results in their being forced down into the rupture or hole in the shoe forming a pocket into which the wall of the inner tube bulges, thus resulting in pinching or rupturing such inner tube as the rupture or hole in the shoe expands and contracts as the wheel revolves and as the inner tube slips circumferentially of the shoe in travel.

Were such flexible or elastic patches applied 55 to the exterior surface of the shoe, the suction and friction of the shoe traveling over the road surface would quickly tear the patch from its position and render its use of no avail.

My patch, when used against the inner

surface of the shoe forms a rigid bridge over the weak spot in the shoe, preventing the bulging of the inner tube down into the blow-out and presenting a smooth surface to the inner tube, continuous with interior surface of the shoe, so that the tube is free to slip circumferentially without danger of pinching or rupturing. When used on the exterior surface of the shoe, the patch cannot be loosened as long as the studs retain their firm grip, and the snug fit of the patch against the shoe is not disturbed by the suction and friction of travel.

My improved patches are much more easily and quickly put in position than the previously designed forms of this general type of patch, and can be manufactured and sold at a much less price. They are also much more durable and efficient in action, and will outwear a tire shoe upon which they are placed.

In the case of operators of large fleets of motor driven vehicles using pneumatic tires, such as department stores in their delivery service, it is the policy to use a tire continuously until worn beyond further service, without vulcanized repairs or patches. In such circumstances, the use of my improved patch is particularly advantageous, as the patches can be quickly put on *en route* and a plurality of patches may be applied to the individual shoe without seriously interfering with its usefulness and service-ability. Thus the life of a tire may be greatly prolonged with a minimum of expense, and tire cost account greatly reduced. This is also a great advantage in connection with military motor vehicles, such as machine gun motors, officers' automobiles and transports, as the repairs may be quickly made *en route*.

What I desire to claim is:—

1. A blow-out patch for pneumatic tires comprising a metal plate conforming to the curvature of the tire shoe and forming a rigid bridge covering the weakened portion of the shoe, said plate being provided with studs extending from the face of the plate through the material of the shoe and clenched on the other surface of the shoe, substantially as and for the purposes described.

2. A blow-out patch for pneumatic tires comprising a plate of ductile metal adapted to conform to the curvature of the tire shoe and forming a bridge covering the weakened portion of the shoe, said plate being provided with integral studs extending from the face of the plate through the material of the shoe and clenched on the other surface of the shoe, substantially as and for the purposes described.

3. A blow-out patch for pneumatic tires comprising a metal plate conforming to the curvature of the tire shoe and forming a rigid bridge covering the weakened portion of the shoe, said plate being provided with

studs extending from the face of the plate through the material of the shoe and clenched on the other surface of the shoe and the exposed face of the plate being provided with rounded corners and beveled edges so as to merge smoothly with the material of the shoe, substantially as and for the purposes described.

4. A blow-out patch for pneumatic tires comprising a plate of ductile metal adapted to conform to the curvature of the tire shoe and forming a bridge covering the weak-

ened portion of the shoe, said plate being provided with integral studs extending from the face of the plate through the material of the shoe and clenched on the other surface of the shoe and the exposed face of the plate being provided with rounded corners and beveled edges so as to merge smoothly with the material of the shoe, substantially as and for the purposes described.

Signed at Pittsburgh, Penna., September, 1917.

JESSE M. SMITH.
